UNITED STATES PATENT OFFICE.

JOHN GIBBONS, OF WEST TROY, ASSIGNOR, BY DIRECT AND MESNE ASSIGNMENTS, OF TWO-THIRDS TO STEPHEN J. BROWN, OF TROY, AND JOHN H. JONES, OF WEST TROY, NEW YORK.

WHEEL AND RAIL BRAKE.

SPECIFICATION forming part of Letters Patent No. 537,191, dated April 9, 1895.

Application filed January 2, 1894. Serial No. 495,313. (No model.)

To all whom it may concern:

Be it known that I, JOHN GIBBONS, a citizen of the United States, residing at West Troy, county of Albany, and State of New York, have 5 invented certain new and useful Improvements in Wheel and Rail Brakes, of which the following is a specification.

My invention relates to such improvements and consists of the novel construction and 10 combination of parts hereinafter described and subsequently claimed.

Reference may be had to the accompanying drawings, and the letters of reference marked thereon, which form a part of this specification.

Similar letters refer to similar parts in the several figures therein.

Figure 1 of the drawings is a central vertical longitudinal section of a car provided with 20 my improved brake. Fig. 2 is a transverse section of the shoe-supporting link taken through the guide-flanges on the broken line 2—2, in Fig. 1, and showing the brake-shoe and rail in top plan. Fig. 3 is a cross-section 25 of the brake-shoe taken on the broken line 3—3, in Fig. 2. Fig. 4 is a view in side elevation of the brake-shoe and its supporting mechanism on an enlarged scale, and detached from the car. Fig. 5 is a top plan view of the 30 yoke-lever for supporting the vertical link to which the brake-shoe is attached.

A represents the car-bottom or floor; A' being the front platform and A² the rear platform, each platform having a dashboard A³.

35 The car rests upon a wheeled truck which may be of any known desired form.

A⁴ represents the truck-frame; A⁵, the springs connecting the truck with the car-body, and A⁶ the car-wheels mounted upon 40 the axles A⁷.

Intermediately of the axles and parallel therewith, I place two rock-shafts B, and B', which have end bearings in the sides of the truck-frame. Each shaft is provided near 45 each end with a rock-lever B² which projects toward the neighboring axle and vertically over one of the track-rails R. Pivoted upon each lever is a pendent link B³ to the lower end of which is pivoted the brake-shoe B⁴. 50 Each rock-shaft is also provided with a rock-lever B⁵.

The rock-levers may be mounted upon a shaft, as shown, or may be pivoted upon the truck-frame in any known manner. Beneath each end-platform, I also provide a rock-shaft 55 B⁶ movable in suitable bearings secured to the lower side of the platform, and provided with a depending rock-lever B⁷. The rock-lever beneath the front platform is connected with the rock-lever B⁵ on the rear rock-shaft 60 B' by a link B⁸; and the rock-lever beneath the rear platform is connected with the rock-lever B⁵ on the front rock-shaft B, by a link B⁹. Each rock-shaft B⁶ is also provided with a rock-lever B¹⁰ adapted to be operated by a 65 foot-pin B¹² inserted through a suitable aperture in the platform-floor and projecting above the floor in a convenient position to be operated by the foot of the brakeman.

The controlling springs B¹³ serve to operate 70 the levers in one direction, and through the connecting mechanism above described to maintain the brake-shoes in an elevated position just above the track-rail, which is the position of the forward shoe as shown in Fig. 1. 75

To apply the brakes, the foot-pin on the front platform is depressed until the shoes in front of the rear wheels strike the track-rails, whereupon the friction between the shoes and rails retards the shoes until they are engaged by the rear wheels and wedged in between the wheels and rails to brake the car by friction both on the rail and on the wheel.

When the brake-shoe is in an elevated position, the shoe-supporting link B rests by 85 gravity against the yoke B¹⁶ of the bifurcate lever B², which yoke serves as a stop.

By making the shoes wedge-shaped with the bit of the wedge next to the adjacent wheel, the wheel will either run up the incline 90 or bear more heavily upon the shoes, when the momentum of the car is checked by the brake, thus increasing the frictional resistance between the shoes and rails to stop the car.

When the car is propelled by an electric motor having a heavy rapidly rotating armature geared to the wheel-axle, some part of the mechanism would be broken if the rotary movement of the wheels were checked too suddenly. As a means for overcoming such danger, I provide each of the shoes with a fric-

tion-roll C upon which the truck-wheels may continue to rotate after they have left the rails until the armature ceases to rotate.

The friction rolls may be severally supported 5 by the pivots C'; and when desired may be supported upon the pivot C² which connects the shoe to its supporting link, in the position of the roll C³ in Fig. 4.

By having the shoes pivotally connected 10 with the respective supporting links, they will when in use always bear throughout their length upon the rails and will not be subjected to such strains as would be imposed with a rigid connection between the shoe and link.

15 I also provide for each shoe and its supporting mechanism guide-flanges C⁴ projecting toward the adjacent wheel and adapted to embrace the rim of the wheel on opposite sides and retain the shoe in the plane of its wheel.

20 The position of the rim of the wheel relatively to the shoe and guide-flanges is indicated by dotted lines C⁵ in Fig. 2. I also provide the bottom of each shoe with a detachable plate or rubber C⁶ which may be made of 25 metal, emery, stone or other desired material.

The rubbing-plate may be detachable and secured to the shoe in any known manner, as by the dove-tailed tongue and groove C⁷.

30 My improved brake is especially adapted for emergencies when the ordinary wheel-brake is inadequate. It is also especially useful as a safety mechanism on steep grades.

35 With the constructions heretofore in use it has been customary to drop the oscillatory end of a dog pivoted to the car, when ascending steep grades, and allow such end to bump along over the pavement, producing a disagreeable noise and vibration as well as wear upon the dog and pavement. Unless dragged

40 upon the pavement the car might, in case of accident, acquire such a backward speed and momentum before the dog could be dropped as to break the dog, or throw the car from the track. I have ascertained that the idle brake-shoes adjacent to the forward wheels, in my 45 improved device, can be made to perform all the useful functions of the dog without the annoyances and dangers incident to the use of a dog.

50 I provide each of the rock-levers B⁵ with a wrist-pin D, and connect the wrist-pins by the rigid links or rods D' with the short ends of a pair of hand-levers pivoted at D³ upon the outer side of the front and rear dashboards respectively. The long ends D⁴ of the levers reach up above the top of the dashboards and afford a convenient means by which the operator can instantly force the forward shoes against the track-rails behind the

wheels, in position to be engaged thereby 60 when the car acquires a backward down grade movement. One great advantage of such a form of construction is that the shoes may be safely applied to resist a down grade movement even after the car has acquired a considerable headway.

65 Each rigid link D' is provided with a slot D⁶ adapted to form a slideway for the wrist-pin D when the brakes are operated by the foot-pins to arrest the forward movement of 70 the car, the pin D sliding along its slot B⁶ and permitting the rigid link D' and hand-lever D' to remain at rest.

75 The brake mechanism is so arranged that the car may be run with either end in advance, but the operator is supposed to occupy the forward platform.

When the rubbing-plate C⁶ is made of metal, as steel, I provide the same with a roughened or file-like surface as shown at C⁸ 80 in Fig. 4.

What I claim as new, and desire to secure by Letters Patent, is—

1. In a wheel-and-rail brake for railway cars, the combination with a pair of brake-shoes and means for movably supporting the shoes one in front and the other in rear of a car-wheel, of a pair of operating levers on each end of the car, and operating connections between each shoe and one of each pair 90 of levers, substantially as described.

2. In a wheel-and-rail brake for railway cars, the combination with a pair of brake-shoes, and means for movably supporting the shoes one in front and the other in rear of a car-wheel, of a foot-lever and a hand-lever on one end of the car, and independent connections between the hand-lever and one shoe, and between the foot-lever and the other shoe, substantially as described.

100 3. In a wheel-and-rail brake for railway cars, the combination with a pair of brake-shoes and means for movably supporting the shoes, one in front and the other in rear of a car-wheel, of a foot-lever and a hand-lever on each end of the car, operating connections between one shoe and the foot-lever on one end of the car and the hand-lever on the other end of the car, and operating connections between the other shoe and the other foot and hand levers, substantially as described.

110 In testimony whereof I have hereunto set my hand this 21st day of December, 1893.

JOHN GIBBONS.
